US0D1020690S

(12) **United States Design Patent** (10) **Patent No.:** **US D1,020,690 S**
(45) **Date of Patent:** **** Apr. 2, 2024**

(54) **EARPHONE**

(71) Applicant: **KYOCERA Corporation**, Kyoto (JP)

(72) Inventors: **Takahiro Watanabe**, Kanagawa (JP);
Junichi Yokoyama, Fukuoka (JP)

(73) Assignee: **KYOCERA CORPORATION**, Kyoto (JP)

(**) Term: **15 Years**

(21) Appl. No.: **29/805,839**

(22) Filed: **Aug. 31, 2021**

(30) **Foreign Application Priority Data**

Jul. 29, 2021 (JP) 2021-016436

(51) **LOC (14) Cl.** **14-01**

(52) **U.S. Cl.**

(57) **CLAIM**

The ornamental design for an earphone, as shown and described.

DESCRIPTION

FIG. 1 is a front view of an earphone showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a perspective view thereof.

The broken lines in the drawings depict portions of the earphone that form no part of the claimed design.

1 Claim, 6 Drawing Sheets
